UNITED STATES PATENT OFFICE.

MAURICE L. BRANDT, OF BROOKLYN, NEW YORK.

DESIGN FOR A HANGER FOR RAZOR-STROPS AND OTHER ARTICLES.

47,584.

Specification for Design.

Patented July 20, 1915.

Application filed June 9, 1915. Serial No. 33,192. Term of patent 3½ years.

To all whom it may concern:

Be it known that I, MAURICE L. BRANDT, a citizen of the United States, residing at Brooklyn, in the county of Kings and State of New York, have invented a new, original, and ornamental Design for a Hanger for Razor-Strops and other Articles, of which the following is a specification, reference being had to the accompanying drawing, in which—

I claim:

The ornamental design for a hanger for razor strops and other articles, as shown.

MAURICE L. BRANDT.
